UNITED STATES PATENT OFFICE.

CHARLES P. MONTO, OF CLEVELAND, OHIO, ASSIGNOR, BY MESNE ASSIGNMENTS, TO
NATIONAL CARBON COMPANY, INC., A CORPORATION OF NEW YORK.

BRUSH CONNECTION FOR DYNAMO-ELECTRIC MACHINES.

1,255,205.

Specification of Letters Patent.

Patented Feb. 5, 1918.

Application filed March 26, 1917. Serial No. 157,347.

To all whom it may concern:

Be it known that I, CHARLES P. MONTO, a citizen of the United States, residing at Cleveland, in the county of Cuyahoga and State of Ohio, have invented a certain new and useful Improvement in Brush Connections for Dynamo-Electric Machines, of which the following is a full, clear, and exact description.

10 This invention relates to flexible connections for brushes of dynamo electric machines and is particularly applicable to graphite-metal brushes.

Referring to the drawings:

15 Figure 1 is a perspective view of the flexible cable to be attached to the brush.

Fig. 2 is an elevation of the metal strip before it is bent around and secured to the cable shown in Fig. 1.

20 Fig. 3 is a perspective view of a brush drilled to receive the flexible cable.

Fig. 4 is a perspective view of the brush with the attached cable.

25 Fig. 5 is a section of the brush shown in Fig. 4 taken on the plane A—A before the head of the screw is removed.

Fig. 6 is a section of a modification.

30 Figs. 7 and 8 are an elevation and plan respectively, of the dowel pin shown in Fig. 6.

Before securing cable 1 to the brush, a strip 2 of brass or other metal is first clamped around the end as shown in Fig. 1. While not absolutely necessary, it is nevertheless preferable to serrate the ends of the strip 2 as at 3 in order to secure a better clamping effect when the ends are turned inward into the strands.

35 The brush 4 to which the cable is to be attached is drilled as at 5 and a small hole 6 formed at right angles thereto. The end of the cable 1 having the clamp 2 thereon is next inserted in the hole 5 with the slit 7 next to the hole 6 as in Fig. 4. A wood screw 8 (Fig. 5) is then screwed into the hole 6 until the point enters the slit 7 and spreads the ends sufficiently to clamp the band outward against the walls of the hole

5. This spreading of the ends 3 also wedges the strands more securely in the band. On account of the soft metallic state of the brush, the screw cuts its own threads and it is unnecessary to tap the hole.

When the screw 8 has been fully inserted it is cut off flush with the side of the brush as shown in Fig. 4 and the connection is complete.

While a wood screw is preferable on account of its tapered end, a pointed machine screw may be used either with or without first tapping out the hole. A pin 9 may also be driven into the hole 6 to secure the cable in place as shown in Fig. 7. In such case it is preferable to knurl the pin 9 as shown in Figs. 8 and 9, as this gives it a better grip on the brush and cable clamp, though a smooth pin may be used if desired.

A brush connection made in accordance with the foregoing disclosure is very strong and of low resistance.

Having described my invention, what I claim is:

1. A contact member consisting of a brush having a cylindrical cavity and a hole substantially at right angles thereto, a stranded conductor having a split metal band around one end, said band being in said cavity and a screw in said hole projecting into the cable between the ends of the split band and wedging the said band against the walls of the cavity.

2. A contact member consisting of a brush having a cylindrical cavity and a hole substantially at right angles thereto, a stranded conductor having a split metal band around one end, the ends of the band being serrated and turned inwardly into the cable, said band being in said cavity and a screw in said hole projecting into the cable between the ends of the split band and wedging the said band against the walls of the cavity.

In testimony whereof, I hereunto affix my signature.

CHARLES P. MONTO.
